(57) **CLAIM**

The ornamental design for an astronomical telescope, as shown and described.

DESCRIPTION

FIG. 1 is an isometric view of the astronomical telescope;

FIG. 2 is a back view thereof;

FIG. 3 is a bottom view thereof;

FIG. 4 is a front view thereof;

FIG. 5 is a left view thereof;

FIG. 6 is a right view thereof; and,

FIG. 7 is a top view thereof.

The broken lines illustrate portions of the astronomical telescope and form no part of the claimed design.
